[57] **CLAIM**

The ornamental design for a universal electronic remote control, as shown and described.

DESCRIPTION

FIG. 1 is a top, left, and rear perspective view of a universal electronic remote control, embodying our new design, the broken line showing of the leash is for illustrative purposes only, and forms no part of the claimed design;

FIG. 2 is a top plan view thereof;

FIG. 3 is a bottom plan view thereof;

FIG. 4 is a top plan view thereof, with the push buttons shown removed for ease of illustration;

FIG. 5 is a right side elevational view thereof, the left side elevational view being a mirror image;

FIG. 6 is a front elevational view thereof; and,

FIG. 7 is a rear elevational view thereof.
